UNITED STATES PATENT OFFICE.

JOHN W. HOLLOWAY, OF NEW YORK, N. Y.

DESIGN FOR A CLOCK-FRAME.

40,502.

Specification for Design.

Patented Feb. 8, 1910.

Application filed December 8, 1909. Serial No. 532,133. Term of patent 3½ years.

To all whom it may concern:

Be it known that I, JOHN W. HOLLOWAY, a citizen of the United States, residing at 550 West One Hundred and Sixty-third street, in the borough of Manhattan, city, county, and State of New York, have invented a new, original, and ornamental Design for Clock-Frames, of which the following is a specification, reference being had to the accompanying drawing, forming part thereof.

The figure is a front elevation of a clock frame, showing my new design.

I claim:

The ornamental design for a clock frame as shown.

J. W. HOLLOWAY.
